UNITED STATES PATENT OFFICE.

FRANCIS POND, OF HINSDALE, ASSIGNOR TO HIMSELF AND W. M. POND, OF CHICAGO, ILLINOIS.

GRAIN-CAR DOOR.

SPECIFICATION forming part of Letters Patent No. 289,445, dated December 4, 1883.

Application filed August 2, 1883. (No model.)

To all whom it may concern:

Be it known that I, FRANCIS POND, a citizen of the United States, residing in Hinsdale, in the county of Du Page and State of Illinois, 5 have invented a new and useful Improvement in Grain-Car Doors, of which the following is a specification.

In grain-car doors heretofore constructed great difficulty is frequently experienced in 10 opening the door when grain or other freight is piled against it, as such doors have ordinarily been so made that they can only be opened in one particular way.

The object of the present invention is to provide 15 a grain-car door that may be opened in a variety of different ways, so that in any emergency it may be easily opened in some one of the different ways. In the present invention the door is hinged at one corner by a two-way 20 hinge to an upright bent rod, which is hinged at top and bottom to the door-casing or side of the car. One of the upper corners of the door is supported by a bent quadrant-shaped rod secured at one end to the back edge of the 25 door, near the top, and at its other end to the bottom edge of the door, near the middle thereof, the space between this quadrant-rod and the side of the door being about equal to the thickness of the vertical rod, so that the door 30 may be revolved in a vertical plane on its lower pivoted corner as a center. The hinge at the corner of the door fits loosely around the upright rod, so that the door may be lifted or slid straight up and down. The bent or bit- 35 stock shaped vertical rod is pivoted at the corner of the casing, and the distance between the straight or vertical part of the rod and the casing is equal to the thickness of the door, so that the door, when it is turned on its pivoted 40 corner, may be turned back between the vertical rod and the casing or side of the car, and also so that the door may be opened or swung outward; in which case the door rests between the vertical rod and the front edge of the casing. By reason of the swinging of the bent 45 rod on its pivots the door may reciprocate back longitudinally far enough to swing past the offset or grooved casing, in which it fits at its front end. By this means it will be seen 50 that the door may be swung or opened either in-

ward or outward; or it may be raised vertically upward and then swung either in or out around the vertical rod; or its front corner may be raised and revolved in a vertical plane around its pivoted corner to the extent 55 of ninety degrees, and then, if desired, swung or turned around the vertical rod as a hinge, so that the door may be opened or closed in a variety of different ways, as may be most convenient.

In the drawings which form a part of this specification, and in which similar letters of reference indicate like parts, Figures 1 and 2 are side elevations of a device embodying my invention, showing the door in different positions. Fig. 3 is a horizontal section, taken just above the quadrant-shaped rod. Fig. 4 is a sectional end view of the car, showing the door swung outward. Fig. 5 is a side elevation, showing the door partially turned on its 60 pivoted corner. Fig. 6 is a cross-section on line 6 6 of Fig. 5, showing the door in position when closed; and Fig. 7 is an enlarged sectional view of the universal or two-way hinge at the corner of the door. Figs. 8, 9, and 10 65 are horizontal sectional views, showing plans of the door when standing on its end and swung into a number of different positions, and Fig. 11 is a similar view of the door resting on its bottom edge.

In the drawings, A represents the door, B the casing or frame of the car, and C is the upright bent rod to which the door is swung. The rod C, at its upper end, has a bend or offset, c, equal in length to the thickness of the 85 door, and is pivoted to the frame of the car by the loop c' at the interior corner of the door-casing B. The lower end of the rod C it is preferable not to bend in this manner, but to secure it to a thin flat horizontal metal arm, 90 c'', which is secured and pivoted to the frame or floor of the car by the pin c''' at the corner of the casing B. By employing the thin flat arm c'' the corner of the door does not require to be much cut out.

The lower or pivotal corner, A', of the door is provided with a two-way hinge consisting of the metallic piece or knuckle D, secured to the door by suitable screws, which receives the pin d, the other end, d', of which is a knuckle 95 100

to receive the upright rod C, upon which it may slide freely, so that the door may slide up and down on the rod C. The lower corner of the knuckle or piece D is notched or cut out, 5 as shown at d^2 , to the thickness of the flat arm c^2 , so that the lower edge of the door will rest flat upon the door-sill or floor of the car and permit of the rod C swinging on its hinges or pivots c' and c^3 .

10 A rod, F, preferably quadrant-shaped, is secured at one end to the back edge of the door, near its top, and at its other end to the lower edge of the door, near its middle, so as to leave sufficient space between the rod and the side of 15 the door for the vertical rod C. The ends of this rod are bent at right angles at e , and should be flattened out and countersunk in the edges of the door, so as to be flush therewith. They may be secured by a single nail or screw 20 when thus countersunk and bent around the edges of the door.

The casing B', at the front or free end of the door, is provided with a jam or shoulder, b, for the door to fit against, and a projecting facing b' , thus forming a groove or guide for this end of the door, as shown in Fig. 3. It may be locked or secured by any ordinary lock or bolt—as, for example, a simple pin, F—passing through the casing and into the edge of the 25 door. The slight sliding or reciprocating motion given to the door by swinging the rod C on its pivots is sufficient to draw the door out from between the casing B' and the facing or flange b' , and allow it to swing open in either direction 30 around the rod C as a hinge. The door may also be lifted directly upward, in which case the shoulder b of the casing and the facing b' furnish a guide or way for one end of the door, while the rod C answers the same purpose for 35 the other end of the door. After the door has been thus raised it may be swung around the rod C as a hinge in either direction. There is sufficient space between the bent rod C and the door post or casing to permit the door to 40 swing freely around said rod, whether the door stands on its end, as shown in dotted lines in Fig. 1, or rests on its bottom edge, as shown in full lines in said figure. The bent rod C being also pivoted or hinged to the door-casing, 45 the rod itself can swing around as the door is swung into different positions, and thus prevent the corner or edge of the door binding against the casing or door-post, as is illustrated in Figs. 8, 9, and 10.

50 G is a pivoted projection provided with a turned-up lip, g, and secured to the side of the car by a pivot or pin, for the purpose of supporting or holding the door when it has been thus opened. The support G is pivoted 55 to the side of the car, so that it may be turned out of the way of the door when it is opened back in other positions than that shown in heavy lines in Fig. 2, and to prevent said support being knocked off or injured when the 60 car is used for handling lumber or other freight than grain. The quadrant-shaped rod E serves 65 to support or hold the door in its vertical

plane when it is being lifted or turned—as, for example, as shown in Fig. 5—and when the door is being swung around the rod C as 70 a hinge, whether it be in its horizontal position, as shown in Figs. 1, 2, 4, or 6, or in its vertical position, as shown in dotted lines in Fig. 1. The bends e , at either extremity of 75 said quadrant-shaped rod, serve as a hinge or knuckle to hinge the upper part of the door to the vertical rod C.

When the door A is turned vertically, so as to stand or rest on its end, as shown in dotted lines in Fig. 1, it may be swung inward around 80 the rod C, as the lower bent end of the quadrant-rod E is secured near the bottom edge of the door in the same manner that the upper end of said rod is secured near the end of the door, and, as the combined pin and knuckle d^2 is secured at the lower corner of the door, 85 the door may swing horizontally, whether it rests on its bottom edge, as shown in solid lines in Fig. 1, or stands on its end, as shown in dotted lines in said figure. 90

I claim—

1. The combination of the bent upright rod C, pivoted to the car, and door A, hinged to said rod by a two-way hinge, so that said door may swing open horizontally or turn around 95 said hinge as a center in a vertical plane, substantially as specified.

2. The combination of bent upright rod C with door A, hinged to said rod by a two-way hinge at one corner of said door, and rod E, 100 extending along the side of said door, from near its upper corner to its lower side, and embracing said rod C between the same and the door, substantially as specified.

3. The combination, with a grain-car door 105 provided with a two-way hinge, of a rod, E, extending parallel with the side of the door, from near its upper corner to its lower side, substantially as specified.

4. The combination of upright bent rod C, 110 pivoted at each end to the car, with door A, provided with corner-piece or knuckle D, pin d , having knuckle d^2 at its other end to receive said rod C, and adapted to slide freely up and down on the same, and casing B', provided with jamb or shoulder b and facing b' , 115 to furnish a guide for the door to slide up and down, substantially as specified.

5. The combination, with swinging door A, adapted also to turn around its hinge in a 120 vertical plane, of bent pivoted rod C, and the two-way hinge securing said door to said rod, consisting of knuckle or corner-piece D, and combined pin and knuckle d^2 , substantially as specified. 125

6. The combination, with a grain-car door A, of guides or means for sliding it upward, and hinges or means for swinging it around, of the pivoted door support or holder G, secured to the side of the car, substantially as specified. 130

7. The combination of the grain-car door A with a rod, E, extending parallel to the side of the door across one of its corners, and pro-

vided with bent ends secured to said door, so that the bent ends of said rod may serve as a hinge on which the door may turn, whether said door rests on its bottom edge, as shown 5 in heavy lines in Fig. 1, or stands on its end, as shown in dotted lines in said figure, substantially as specified.

8. The combined vertically-sliding door A, hinged so as to support the door when swung 10 open horizontally, and vertically turning, substantially as specified.

9. The combined vertically-sliding door A, hinged so as to support the door when swung

open horizontally, reciprocating and vertically turning, substantially as specified. 15

10. The combination, with the door A, provided with a two-way hinge near one corner, of means for supporting and swinging the door horizontally, whether it stands on its end or bottom side, substantially as specified.

Chicago, July 28, 1883.
